UNITED STATES PATENT OFFICE.

WILLIAM C. HOYT, OF HOPKINTON, ASSIGNOR OF ONE-HALF TO FRED A. PIPER, OF CONCORD, NEW HAMPSHIRE.

GARMENT-SUPPORTER.

SPECIFICATION forming part of Letters Patent No. 517,278, dated March 27, 1894.

Application filed July 24, 1893. Serial No. 481,337. (No model.)

To all whom it may concern:

Be it known that I, WILLIAM C. HOYT, a citizen of the United States, residing at Hopkinton, in the county of Merrimac and State 5 of New Hampshire, have invented certain new and useful Improvements in Garment-Supporters; and I do hereby declare the following to be a full, clear, and exact description of the invention, such as will enable others skilled in 10 the art to which it appertains to make and use the same.

My invention relates to devices for supporting garments, such as hose, skirts, or other apparel, the object of the invention being to provide 15 a simple and effective clasp which will not be liable to tear the object to which it is attached.

The invention will be fully set forth in the following specification and claims, and clearly 20 illustrated in the accompanying drawings forming a part thereof, of which—

Figure 1. is an elevation of my improved device shut together as when clasping an article, Fig. 2. being an end view of same. Fig. 25 3. is a plan of my improved clasp, showing a portion of an elastic or other strap by which it may be connected to a belt or waist-band, and a portion of an article closed within said clasp; and Fig. 4 is a side view of a clasp or 30 fastener showing the jaws provided with a facing of yielding material.

Similar reference letters denote corresponding parts.

The clamping lever A, having the projection B, with the part D, are pivoted respectively at I, and J, to the ears H, projecting at each side of the frame G, provided at one end with an elongated opening g, for inserting one end of an elastic or other strap X, as seen 40 in Figs. 1 and 3.

The adjacent surfaces of the parts D—G. may be faced with rubber or other elastic material as shown respectively at E—F, so as to be more adhesive without danger of 45 damaging the goods to be pressed between them, or the parts D—G may be corrugated crosswise and arranged to closely fit each other when closed;—and the part D, is provided with a catch C, at its outer end, to receive 50 and secure the clamping lever A, in the position shown in Fig. 1.

The spring catch C, may be formed integral with the part D, or secured thereon by rivets K, as seen in the drawings.

As shown in the drawings, the pivotal point 55 of the parts A and D are at different distances from the part G so that their free ends swing in the arcs of different circles and the pivotal point I is preferably located forward of the point J so that the differences between the 60 arcs are increased. With such a location and construction of the parts it is evident that when the parts A and D are swung toward the part G, the end of the part A, which is preferably shorter than the part D, will 65 move inward relatively to the end of the part D. By the time that the part D has been brought into contact with the part G the end of part A is moved inward relatively thereto so that it will pass behind the catch C and will 70 lock the part D against the return movement until the ends are disengaged, as by bending the catch C out far enough to release the end of the part A.

To reduce my improved clasp or garment 75 supporter to practice the parts D—G, are separated as in Fig. 4, and the article to be attached—such as T, in Fig. 3,—is passed in between them;—then by pressing the outer end of the clamping piece A, the parts D—G, 80 or E—F, are brought together, and the spring catch C, which was forced outward by the end of the lever A, has returned to its normal position and over or outside of the said lever A, thus firmly holding the article T—between 85 the parts D—G. The object of the projection B, being to exert a pressure upon the part D, and prevent its springing at that point.

Having described my invention, what I 90 claim is—

1. In a garment or hose support, a main frame or bracket having at one end an opening for fastening an elastic or other strap, and provided near said opening with ears, one at each side, projecting at right angles upward, 95 a frame pivoted at one end to said ears and provided at its free end with a suitable spring catch, and a clamping lever pivoted at one end to the ears of the main frame, having a lug near said pivoted end for contact with 100 said pivoted frame and having its free end adapted to pass under said spring catch.

2. As a new article of manufacture, a clasp consisting of three members, two of which are pivotally secured to the remaining member eccentrically to each other, the free ends of which two pivoted members are provided with means for interlocking with each other when the clasp is closed, substantially as set forth.
3. As a new article of manufacture, a clasp consisting of three members, two of which are pivotally secured to the other member, one above the other, the inner one of said pivoted members being provided at its outer end with

a shoulder against which the outer end of the other pivoted member when the clasp is closed will engage and lock said inner member against a return movement, substantially as set forth. 15

In testimony whereof I affix my signature in presence of two witnesses.

WILLIAM C. HOYT.

Witnesses:

J. B. THURSTON,
CARRIE E. EVANS.
